Primary Examiner — Nathan M Johnston(74) *Attorney, Agent, or Firm* — Joseph E. Maenner; Maenner & Associates, LLC(57) **CLAIM**

The ornamental design for a for a clip for medical tubing, as shown and described.

DESCRIPTION

FIG. 1 is a front perspective view of an ornamental design of a clip for medical tubing showing our new design.

FIG. 2 is a top plan view thereof.

FIG. 3 is a bottom plan view thereof.

FIG. 4 is a front elevational view thereof.

FIG. 5 is a rear elevational view thereof.

FIG. 6 is a right side elevational view thereof; and,

FIG. 7 is a left side elevational view thereof.

The dashed lines immediately adjacent to the shaded areas in the figures represent the boundaries of the claimed design. The dashed lines in the figures illustrate the portions of the design that form no part of the claimed design. None of the broken lines form any part of the claimed design.
